108 INVENTION

R. B. Tolman ATTORNEY.

UNITED STATES PATENT OFFICE.

FREDERIC BARR, OF NEW YORK, N. Y.

ELECTRIC SWITCH.

1,185,579.

Specification of Letters Patent. Patented May 30, 1916.

Application filed March 13, 1914. Serial No. 824,369.

To all whom it may concern:

Be it known that I, FREDERIC BARR, a citizen of the United States of America, and residing at New York, in the county of 5 Kings and State of New York, have invented new and useful Improvements in Electric Switches, of which the following is a specification.

This invention relates particularly to 10 switches of the so-called "key socket" type.

The main object of my invention is to provide a simple, inexpensive, compact, reliable and positive acting switch of high current carrying capacity.

15 The invention is preferably embodied in mechanism adapted to break the circuit at two points so as to reduce arcing effects and preferably the device is constructed so as to interrupt the arc.

20 The switch preferably embodies a rotary switch element whose movement is accelerated by a throwing spring which engages a cam connected with the rotary switch element. Preferably this throwing spring carries no current and independent spring contacts are provided which are arranged to bear against the rotary switch element.

The throwing spring preferably extends longitudinally of the switch spindle and is 30 preferably housed in an independent chamber in the insulating switch base separated from the spindle and from the outside of the base by insulating walls.

The invention may be embodied in insulating switch bases of one-piece and two-piece construction.

Other features of the invention will appear as the specification proceeds.

In the accompanying drawings I have 40 illustrated several practical embodiments of different features of my invention.

Figure 1, is a longitudinal sectional view of a two-piece base, double-break switch construction in which the rotary switch member is carried by an arc-interrupting insulating block and the throwing cam is in the form of a metallic member connected to the insulating block. Fig. 2, is a partial sectional view of the same taken substantially on the 45 plane of the line 2—2 of Fig. 1. Fig. 3, is a perspective drop view of the key spindle, throwing spring, switch contacts and arc interrupter. Fig. 4, is a face view of the arc-interrupting switch block which carries the

55 rotary switch member. Fig. 5, is a view of the back or reverse side of the same. Fig. 6, is a longitudinal sectional view of a one-piece insulating base construction embodying the general features of the construction shown in the preceding figures. Fig. 7, is a 60 sectional view of the same taken substantially on the plane of the line 7—7 in Fig. 6. Fig. 8, is a longitudinal sectional view of a two-piece base construction in which the rotary switch element is mounted direct on the spindle and the throwing cam is made 65 an integral part of the same. Fig. 9, is a partial sectional view taken substantially on the plane of the line 9—9 in Fig. 8. Fig. 10, is another sectional view taken substantially 70 on the plane of the line 10—10 in Fig. 8. Fig. 11, is a plan view of the upper member of the porcelain or like insulating base employed in this construction. Fig. 12, is a view of the underside of this so-called top 75 porcelain. Fig. 13, is a view of the upper face of the lower porcelain. Fig. 14, is a bottom plan view of the lower porcelain. Fig. 15, is a detail view of the insulating 80 disk or washer which closes the lower side of the spring chamber in this construction. Fig. 16, is a drop perspective view of the spindle, throwing spring and switch contacts in this form of the invention. Fig. 17, is a side elevational view of a one-piece base 85 construction having features in common with the construction shown in Figs. 8 to 16. Fig. 18, is a view looking in the direction of the arrow in Fig. 17, with the spindle and the screw shell shown in section. Fig. 19, 90 is a plan view of this construction. Fig. 20, is a longitudinal section taken substantially on the plane of the line 20—20 in Fig. 19. Fig. 21, is a transverse sectional view taken substantially on the plane of the line 21—21 95 of Fig. 20, with the spindle omitted. Fig. 22 is a bottom plan view of the insulating base in this form. Fig. 23, is a longitudinal sectional view of a form of construction similar to that shown in Figs. 17 to 22 but wherein 100 the throwing spring is used to carry current. Fig. 24, is a part sectional view of this form looking in the direction of the arrow in Fig. 23.

The base of the switch is made of suitable 105 insulating material, such as porcelain, and may be of one piece or two piece construction, as desired. When made in two pieces,

it consists of an upper member 30 and a lower member 31, suitably united as by means of through screws, one of which appears at 32 in Fig. 9.

5 Journaled in a transverse passage 34 in the base is an operating spindle 35, usually provided with a key or handle 36. For convenience in assembling, this spindle passage, is, in the two-piece structure usually provided by forming channels or recesses 34' in the meeting faces of the two blocks (Figs. 12 and 13) which, when the blocks are assembled coöperate to form the complete spindle passage. The turning of the spindle 10 is facilitated by providing it with flanged bearing sleeves or bushings 37 which are clamped between the two blocks.

15 A switch chamber 39 is formed in the base at one end of the spindle passage and 20 mounted on the spindle within this chamber is the rotary switch element and throwing cam.

In the first form of the invention the rotary switch element consists of a contact 25 plate 40 carried by an arc-interrupting insulating block 41 and the throwing cam is in the form of a cam-shaped metallic member 42 suitably connected with the insulating block. In the specific construction illustrated, the arc-interrupter 41 is of substantially oval or elliptical shape and is provided with a recess 56 in its face to receive the contact plate 40 which is thus disposed transversely of the spindle. To provide the 30 necessary contacts, the end portions 43 of the plate 40 are bent over into notches 44 in the end edges of the switch block coextensive with the recess in the face of the block and the plate is shown secured to the 35 block by bending its extreme end portions 45 down into the coextensive recesses 46 in the back of the block. At the sides, the contact plate is protected by the outstanding side flanges 47 of the block and, it is protected from contact with the spindle by the 40 central projecting hub 48, the plate having a central opening 49 to receive this hub. This insulating hub 48 usually projects a distance greater than the thickness of the plate, 45 so that it will, as indicated in Fig. 1, prevent any possibility of the contact plate ever engaging with the metal washer 50 or other device which may be used for positioning the parts on the spindle. The positioning 50 washer 50 is usually slotted so that it may be engaged edgewise with the slotted portion 55 51 of the spindle.

The connection between the insulating switch block and the metallic throwing cam 60 42, is, in the illustration, accomplished by providing the switch block with an angular boss 52 (see Fig. 5) on its rear face which fits into an angular recess 53 in one face of the cam. The other face of the throwing 65 cam is shown provided with a transverse re-

cess 54, which receives a transverse pin 55 on the spindle. This construction provides a lost-motion connection between the spindle and cam and as the switch block moves with the cam, the switch block is thus loosely keyed on the spindle.

60 is the throwing spring, which by its engagement with the cam, serves to throw the rotary switch member with a quick snap action. In its preferred construction this 75 spring is made of flat spring metal with a relatively flat base portion 61 and a spring arm 62, bent back over the base portion substantially parallel therewith, and carrying a widened contact face 63 also substantially 80 parallel with the base portion and adapted for engagement with the relatively wide contact face of the cam. The spring of this construction is powerful and at the same time is so compact as to take up but very 85 little room in the switch body. As the flexibility and strength of the spring is dependent to an extent upon its length, I prefer to place it longitudinally of the spindle 90 so that it may be made as long as necessary to give the best spring action. This longitudinal disposition of the throwing spring is clearly illustrated in Fig. 1 and this view also illustrates how this spring is preferably housed in a chamber 65 substantially parallel to the spindle passage and separated therefrom by an insulating wall 66. This chamber is preferably closed to the outside by an insulating wall 67, which in the constructions shown in Figs. 1 and 8, is provided by a disk or washer 68 (Fig. 15) of 95 insulating material, secured to the lower porcelain by screws 69, (Fig. 2).

The throwing spring is preferably secured direct to the insulating base and is shown 105 so secured by a screw 70 and nut 72. The insulating base has a hole 71 to receive this screw and the base portion of the spring has a screw opening 73. If the metal of the throwing spring is heavy enough the nut 110 may be dispensed with and the screw be engaged direct in the base portion of the spring. To prevent the free end of the throwing spring from engaging against the securing means when the spring is compressed, the spring is usually made with a neck portion 75 at the end of the spring arm inclined away from the base portion so as to support the contact end of the spring 115 away from the base portion far enough to leave room beneath it for the necessary securing means.

The relatively stationary switch contacts are designated 77 and 78, the upper one, 77, being in the first form of construction, shown 120 as secured to the upper porcelain by a screw 79 and the lower one, 78, secured to the lower porcelain by a screw 80. Since the work of throwing the rotatable switch member is done by the throwing spring these contacts 125

may be in the form of relatively light springs which need only bear lightly on the rotary switch member and with pressure just sufficient to insure good contact. On account of the elliptical cam shape of the switch block these springs do however assist somewhat in throwing the movable switch member into the "off" position. Preferably the relatively stationary contacts are, as clearly indicated in Figs. 2 and 7, spaced apart on opposite sides of the spindle, a distance greater than the minor axis of the switch block and substantially equal to the major or longer axis of the block, as a result of which they do not touch the block in the off-circuit position, as indicated in dotted lines in Fig. 7. Consequently no matter how much the switch is used the metal of the contacts can never scrape off and form a short circuiting metal coating around the block. Usually the block is made of porcelain, the surface of which may be glazed to provide a smoother surface and reduce friction.

From the foregoing it will be evident that as the spindle is turned, the throwing cam places the throwing spring under compression until the corner of the cam passes under the center of the spindle, whereupon the spring rebounds and forcibly throws the cam and with it the switch member into the next position. The parts are so proportioned that the switch member will be thrown in this way as the circuit is just about to be broken. This quick movement materially reduces the tendency to arc but in addition to this it will be noted that the surface of the switch block forms an insulating barrier which interposes itself between the relatively stationary and movable contacts at the time of circuit interruption and positively cuts or disrupts the arc which otherwise might start. This makes it possible for the switch to carry a heavy load without danger. This current carrying capacity is further increased by reason of the fact that since the stationary contacts do not have to possess any inherent spring qualities, they may be made large and heavy enough to carry the desired current. The mounting of the movable switch member on the insulating support prevents current from reaching the spindle and the making of the cam member of metal permits the use of any desired spring pressure for throwing purposes without wearing or injuring the insulating switch block.

Suitable switch terminals are provided, these terminals, in the illustrations taking the form of the line terminals 83 and 84 and the lamp terminals 85 and 86. One of the line terminals (83) is in the first form shown, connected with the upper switch contact while the other one (84) receives the screw 69 extending up from the screw shell

lamp terminal 85. The center lamp terminal 86 is connected by the screw 80 with the lower switch contact 78.

Figs. 6 and 7 illustrate an embodiment of the invention in a one-piece base construction. Here the switch base 90 is made in a single piece, instead of in two pieces, the other features of construction being substantially the same as just described, it being noted that in this case also the base is formed with a switch chamber and with parallel spindle passage and spring chamber intersecting and opening into the switch chamber. Fig. 7 furthermore, shows a screw 91 which may be used in addition to the screw 69 for securing the screw shell to the base.

The two-piece construction illustrated in Figs. 8 to 19 is somewhat simpler and less expensive to make than the first two forms described for the reason that the rotatable switch member and the throwing cam are both made of metal and integral with each other. This composite member, as best shown in Fig. 16, is in the form of a metal block 93, which is keyed loosely on the spindle by a transverse pin 94, engaging in a notch 92 in the forward edge of the block. This block is provided with the widely spaced contact faces 95 for engagement with the relatively stationary switch contacts and at the rear with the cam faces 96 to be engaged by the contact portion 63 of the throwing spring.

Figs. 17 to 22 illustrate a one-piece construction which except for this feature is similar in a general way to the two-piece structure just referred to. In this case the switch base 98 is made in a single piece and is provided with the switch chamber 39 and the intersecting spindle passage 34 and spring chamber 65 as heretofore described. The spring chamber is in this case formed in the upper part of the base, substantially the same as in the one-piece structure shown in Fig. 6, and the throwing spring is secured therein by a screw 99 passed down through a screw hole 100 in the top of the base.

The one-piece structure shown in Figs. 23 and 24 is practically the same as that just described except that in this case the throwing spring 60 is utilized to carry current. It is for this purpose, shown as connected with a circuit terminal 103 by securing screw 104. This dispenses with the need for the upper switch terminal and thus reduces expense of manufacture. A further saving is effected by reason of the fact that a simple cam such as indicated at 105 having only one set of end contact faces 106 and flat sides 107 may be used here in place of the previously described cam (93) which has contact faces for the switch contacts and separate contact faces for the throwing spring. The circuit in this case is from circuit terminal 103, through the throwing spring 60,

across the cam 105 to the lower switch terminal 78 and, by way of a securing screw 108 to the center lamp contact 86, and from the other lamp terminal 85 by way of securing screw 69 to the other circuit terminal 84.

The last two constructions described are so nearly alike that the same porcelain may be used either for a double-break switch like that shown in Figs. 17 to 20 or for a single-break switch like that shown in Figs. 23 and 24. For the sake of this interchangeability, I have shown the porcelain provided with the screw hole 100 approximately at the center of the block to receive the screw 99 when making up the double-break construction (Fig. 20) and with an extra screw hole 111 nearer the edge of the block to receive the securing screw 104 when making up the single-break construction. The unused screw hole may be plugged up in any suitable way. Instead of providing two screw holes, a single screw hole might be provided and the throwing springs be made to suit a double cam 93 like that shown in Fig. 20 or a single cam like that shown in Fig. 23.

From the foregoing it will be seen that there are a number of advantages in the invention. The parts are so constructed and arranged that the insulating base and the metal parts can be easily made and assembled. The method of mounting and housing the metal parts insures proper insulation. By using a powerful throwing spring and a relatively slow acting contact spring it is possible to obtain a quicker break of the circuit. The insulating carrier for the rotary switch contact prevents the drawing out of an arc when the circuit is broken. It will be obvious that a device may be so constructed as to have only a part of these advantages.

As the constructions illustrated may be varied somewhat and still embody features of the invention, it will be understood that the terms employed in the claims are terms of description, rather than of limitation, except so far as may be required by the prior art.

What I claim is:

1. In an electric switch, an insulating base provided with a transverse spindle passage and with a spring chamber separated from said spindle passage and from the outside of the base by relatively stationary insulating walls, a spindle seated in the spindle passage, a cam on the spindle adjacent the end of the spring chamber and a throwing spring mounted in the spring chamber and extending longitudinally of the spindle but separated therefrom by one of the relatively stationary insulating walls aforesaid and projecting out of the end of said chamber into engagement with the cam on the spindle.

2. In an electric switch, an insulating base provided with a transverse spindle pas-

sage and with a spring chamber disposed parallel to the spindle passage and separated from said passage by an insulating wall and having a screw hole opening from the outside into said spring chamber, a spindle seated in the spindle passage, a cam on the spindle adjacent one end of the spring chamber, a throwing spring mounted in the spring chamber extending longitudinally of the spindle but separated from the spindle by the insulating wall aforesaid and projecting from the end of said chamber into engagement with the cam, and a screw seated in the screw hole and securing the throwing spring directly to the insulating base.

3. In an electric switch, an insulating base having closed upper and lower ends and provided with an intermediate switch chamber, a transverse spindle passage intersecting the switch chamber and a transverse spring chamber intersecting the switch chamber and disposed parallel to the spindle passage and separated therefrom by an insulating wall, a key spindle seated in the spindle passage, a cam on said spindle located in the switch chamber substantially at the intersection of the switch chamber by the spring chamber, and a throwing spring mounted in the spring chamber and extending longitudinally out of the spring chamber into engagement with the cam.

4. In an electric switch, an insulating base, a key spindle journaled in the base, a relatively flat faced cam on said spindle, and a throwing spring having a relatively flat base portion secured to the insulating base, a spring portion doubled back over the base substantially parallel thereto, a neck portion at the end of said spring portion bent up at an angle therefrom away from the plane of the base portion and a contact portion at the end of the said inclined neck portion disposed substantially parallel to the spring portion and wider than the neck portion to make a wide bearing engagement with the relatively flat face of the cam.

5. In an electric switch, an insulating base, a spindle journaled in the base, spaced apart switch contacts secured to the base at opposite sides of the spindle, an arc-interrupting insulating block keyed on the spindle having a length substantially equal to the distance between the switch contacts, a switch contact carried by and extending lengthwise of said block with its ends exposed at the end edges of said block whereby to engage the relatively stationary switch contacts when said switch block is turned with its length in line with the space between said switch contacts, said switch block having a width less than the distance between the switch contacts to thereby become disengaged from both switch contacts when said switch block is turned with its

- width in line with the spaced apart switch contacts, a cam on the spindle and a throwing spring engaging the said cam.
6. In an electric switch, an insulating base 5 provided with a transverse spindle passage and with a spring chamber separated from said spindle passage and from the outside of the base by insulating walls, a spindle seated in the spindle passage, an arc-interrupting insulating block keyed on said spindle and provided with a cam disposed adjacent the end of the spring chamber, a transversely extending movable switch contact carried by said block and having its 10 ends exposed at the opposite edges of said block, relatively stationary switch contacts on the base adapted to be engaged by the exposed ends of the movable switch contact and a throwing spring mounted in the 15 spring chamber and extending longitudinally of the spindle but separated therefrom by the insulating wall aforesaid and projecting out of the end of said chamber into engagement with the cam.
- 20 7. In an electric switch, an insulating base provided with a transverse spindle passage and with a transverse spring chamber separated from the spindle passage and from the outside of the base by relatively stationary 25 insulating walls, a spindle journaled in the spindle passage, an oval-shaped arc-interrupting insulating block keyed on the spindle, a switch contact extending across one face of said insulating block along the 30 major axis thereof and having its ends bent over the edges of the block to provide exposed contact portions, relatively stationary switch contacts on the base spaced apart a distance less than the major axis and greater 35 than the minor axis of the oval-shaped insulating block in position to be engaged by the exposed contact portions of the movable switch member, a cam on the spindle and a throwing spring disposed in the switch 40 chamber parallel to the spindle having a base portion secured directly to the insulating base and a spring arm portion doubled back over the said base portion and engaging the cam aforesaid.
- 45 8. In an electric switch, the combination of an insulating base, a spindle journaled therein, an arc-interrupting insulating block keyed on said spindle, a transversely disposed switch contact extending across one 50 face of said block and having its ends bent over the edges of the block to form contact portions, outstanding flanges on the face of the insulating block inclosing the side edges of the transversely extending switch contact and terminating at the points where the end contact portions are bent over the edges of the block and relatively stationary switch contacts on the base disposed at opposite sides of the spindle and facing toward the spindle to be thereby engaged by 55
- the end contact portions of the relatively movable switch contact.
9. In an electric switch, an insulating base, a spindle journaled therein, an arc-interrupting insulating block keyed on said spindle and provided with a projecting hub and with side flanges outstanding from one face thereof, a transversely extending contact plate received between the side flanges of the insulating block and provided with an opening receiving the hub of the block, said plate having its ends bent over the edges of the insulating block to form contact portions, securing means on the spindle adapted to bear against the insulating hub 70 of the switch block and relatively stationary switch contacts on the base in position to be engaged by the contact portions of the contact plate.
10. In an electric switch, an insulating base, a spindle journaled in the base, an insulating block keyed on said spindle and provided with a transversely extending recess in one face thereof and with peripheral recesses communicating with said transversely extending recess, a switch contact seated in the transversely extending recess and having its ends bent over into the peripheral recesses in the insulating block to form contact portions, relatively stationary 80 switch contacts on the base adapted to be engaged by the end contact portions of the transversely extending movable switch contact, a cam carried by the switch block and a throwing spring engaging said cam to 85 throw the said switch block.
11. In an electric switch, an insulating base, a spindle journaled in the base, an insulating block keyed on said spindle and provided with a transversely extending recess in the face thereof, peripheral recesses in opposite edges thereof communicating with the said transverse recess and recesses in the back thereof communicating with the peripheral recesses, a switch contact seated 90 in the transversely extending recess and having its ends bent over into the peripheral recesses and down into the recesses in the back of the insulating block, and relatively 95 stationary switch contacts adapted to be engaged by the peripheral portions of the movable switch contact.
12. In an electric switch, an insulating base, a spindle journaled in said base, an insulating block loosely engaged on the spindle and provided with an angular boss on one face thereof, a switch contact carried by said insulating block, relatively stationary switch contacts on the base adapted to be engaged by the movable switch members, a cam member loosely engaged on the spindle, provided with an angular recess in one face fitting the angular boss on the insulating block and with a transversely extending recess in its opposite face, and a trans- 105
- 110
- 115
- 120
- 125
- 130

versely extending pin carried by the spindle and engaging in the transverse recess in the face of the cam member.

13. In an electric switch, a rotatable spindle, an angular member carried thereby, a strong throwing spring coacting with said angular member, an oval shaped insulating arc-interrupting member mounted on said spindle having a transverse recess extending 10 across one face and along the major axis thereof, a contact member seated in said transverse recess and having contact faces exposed only at the ends of the major axis of said insulating member and a pair of 15 relatively weak contact springs adapted to engage the said contact faces as the same are rotated by said spindle, said insulating member being adapted to interrupt the arc which tends to form when the circuit is 20 broken.

14. In an electric switch, an insulating base, a spindle mounted thereon, a movable switch contact disposed transversely of the spindle and having contact portions at its 25 ends disposed parallel to the spindle, an elongated insulating carrier for the movable switch contact engaged on the spindle and provided with recesses in its ends receiving the contact portions of said switch 30 contact, said carrier having rounded and glazed bearing surfaces adjacent the exposed faces of the said contact portions, a contact spring arranged to bear relatively lightly on the contact portions and the 35 rounded glazed insulating surfaces adjacent thereto, a cam connected with the insulating carrier and a relatively powerful throwing spring engaging the said cam.

15. In an electric switch, an insulating 40 base provided with a switch chamber in one

face thereof, a transverse spindle passage intersecting said chamber and a spring chamber extending from the switch chamber transversely into the body of the base 45 parallel to the spindle passage and separated from said passage and from the outside of the base by insulating walls, a spindle journaled in the spindle passage, a reversely bent spring seated in the spring chamber extending longitudinally of the 50 spindle and having a free end projecting out of the spring chamber into the switch chamber, means securing said spring to the insulating base and a cam on the spindle within the switch chamber engaged by the 55 free end of the spring.

16. In an electric switch, an insulating base provided with a switch chamber in one face thereof, a transverse spindle passage intersecting said chamber and a spring 60 chamber extending from the switch chamber transversely into the body of the base parallel to the spindle passage and separated from said passage and from the outside of the base by insulating walls, a spindle journaled in the spindle passage, a throwing spring seated in the spring chamber 65 having a flat base secured to the insulating base and a reversely bent spring arm projecting out of the spring chamber into the switch chamber, a terminal secured in flat engagement with the flat base of the spring and a metal cam on the spindle within the switch chamber in position to be 70 engaged by the projecting free end of the 75 throwing spring.

FREDERIC BARR.
